UNITED STATES PATENT OFFICE.

WILLIAM H. HOPKINS, OF CHICAGO, ILLINOIS, ASSIGNOR TO WILLIAM THOMPSON & CO., OF SAME PLACE.

ICE-CREAM FREEZER.

SPECIFICATION forming part of Letters Patent No. 486,779, dated November 22, 1892.

Application filed February 20, 1892. Serial No. 422,219. (No model.)

To all whom it may concern:

Be it known that I, WILLIAM H. HOPKINS, a citizen of the United States, residing at Chicago, in the county of Cook and State of Illinois, have invented certain new and useful Improvements in Ice-Cream Freezers, of which the following is a full, clear, and exact description, that will enable others to make and use the same, reference being had to the accompanying drawings, forming a part of this specification, in which—

Figure 1 is a side elevation and part section; and Fig. 2, a broken-away enlarged section, showing the freezing-tub and cream-receptacle.

This invention relates more especially to improvements in power-freezers, and has for its object to provide a machine of this character wherein the driving mechanism is greatly simplified and made more durable and the freezing-receptacle more easily inserted or removed, as will be hereinafter set forth.

Referring to the drawings, A is the frame or supporting-pedestal, comprising the enlarged hollow or chambered base a and the hollow standard a', having the overhanging head-piece or bifurcated end a², forming a recess back from the front to receive the geared driving mechanism. The branch arm a³ of the frame supports the back journal-bearing a⁴ of the driving-shaft B, on the rear part of which are mounted a fly-wheel B' and band-pulleys B² B³, belting with the motive power. The front end of the horizontal driving-shaft 30 passes through and is journaled in the head-piece of the frame and projects far enough into recess a⁵ between the forked end to have the miter cog-wheel C, mounted on the terminal end thereof, as shown in Fig. 1. The collar a⁶, mounted on the driving-shaft back of the front bearing, serves to retain the shaft in its proper position against a forward thrust or movement. The respective fork ends of the head-piece are perforated vertically to provide bearings for the prolonged hub or sleeve parts of the miter cog-wheels D and E, which are arranged in the relative position shown with reference to cog-wheel C—that is, at right angles above and below the same. The sleeve

50 part b of the wheel D is retained in place by collar b', secured to the upper end, and is rigidly mounted on the upper part of spindle F. The cog or gear wheel D engages with companion wheel C on the upper side. The hub or sleeve extension b² of companion wheel E 55 loosely incloses the lower part of spindle F. The end of this sleeve extends below the end of the inclosed spindle and is provided with a square recess or socket b³, adapted to receive the correspondingly - shaped shoulder b⁴, 60 formed centrally on the exterior top of the cover b⁵ of the cylindrical cream-receptacle G. This cover b⁵ is attached to the said receptacle by means of any suitable fastening device, whereby any motion imparted to one will also 65 be imparted to the other. The lower end of spindle F, stopping short of socket b³, is provided with a recess d, so as to receive or engage with the upper flattened end d' of the agitator or dasher shaft H, projecting up 70 through the shoulder formation of the cover. The cog-wheel E engages with the under side of the driving-wheel C. By this arrangement the cream-receptacle is rotated in one direction and the agitator or dasher H' in the opposite direction as the companion wheels D and E are driven in opposite directions. The movable platform J is mounted on the supporting-base just under the overhanging part 75 of the frame in which the driving mechanism is journaled. This platform is provided centrally on the under side with a lug d², extending down into the chambered supporting-base. A horizontal rocking lever K is located in the base and is mounted on the pivot or fulcrum-pin d³. The forward end of this lever is pivoted, as at d⁴, to the lug d². The opposite end of this lever is pivoted, as at e, to the lower end of the rack-bar L, extending upwardly inside of the frame-standard. This 80 rack-bar is provided with a series of teeth e', with which pinion e² engages. This pinion is mounted on shaft e³, journaled in the supporting-standard. On the outer end of shaft e³, outside of the standard, is mounted 85 gear-wheel e⁴. (Indicated by dotted lines.) The crank-shaft g is also journaled in the supporting-standard and has pinion g' mounted thereon, which engages with gear-wheel e⁴. One end of hand-crank g² is mounted on said 90 crank-shaft, the opposite end being provided with handle g³. Pawl g⁵ locks pinion g' in a

stationary position. By this arrangement and connection of mechanism described platform J may be raised or lowered, as required. The platform is shown in its lowermost position, ready for the placing of the freezing-tub thereon. When the tub containing the cream-receptacle is placed in position, the hand-crank should be turned in the proper direction to force the rack-bar downwardly, which movement will elevate the platform, so as to throw the shoulder on cover b^5 and the flattened end d' of agitator-shaft H into engagement with the socket-bearing in lower end of sleeve b^2 and the recess d in the lower end of spindle 10. 15 F. When the process of freezing is completed, the platform is dropped in the same manner, the tub removed and replaced by another, thus conveniently and quickly engaging with or disengaging from the rotary mechanism. 20 The movable platform is provided with a number of clamping-bolts g^6 , which may be set to retain the tub in proper position with reference to the rotating mechanism. 25 The lower or bottom end h of the cream-receptacle is provided with the bearing-boss h' recessed in the under side to receive the conical bearing-point h^2 , projecting upwardly from the plate h^3 , fastened to the interior bottom of the inclosing tub P. The lower end of the 30 dasher-shaft terminates in the bearing-point h^4 , which seats in a corresponding recess formed in the upper side of boss h' . The annular space between the inclosing tub and the cream-receptacle is for the reception of the 35 ice or freezing composition.

Having thus described my invention, what I claim as new, and desire to secure by Letters Patent, is—

1. In a freezing apparatus of the character 40 described, the combination, with the freezer proper and mechanism for rotating the movable parts thereof, of a vertically - movable platform carrying said freezer, a rocking lever pivoted at one end to the under side of 45 said platform, a rack-bar pivoted at its lower end to the opposite end of the rocking lever, and means, substantially as described, for imparting a vertical endwise movement to said

rack-bar, whereby said platform may be elevated or depressed, substantially as described. 5c 55 2. In a freezing apparatus of the character described, the combination, with the freezer proper, and mechanism for rotating the movable parts thereof, of a vertically - movable platform, a rocking-lever pivoted at one end thereto, the rack-bar pivoted at its lower end to the rear end of the rocking lever, the pinion engaging with the toothed end of said bar, the gear-pinion mounted thereon and engaging with said gear-wheel, and means for rotating said crank-shaft, substantially as described. 60

3. In a freezing apparatus of the character described, the combination, with the freezer proper and mechanism for rotating the movable parts thereof, of a supporting-frame comprising a chambered base and hollow standard, a vertically-movable platform adapted to receive the freezer and mounted on said base and having a projecting part extending down 70 into the chamber, a rocking lever located in said chamber and pivoted at its front end to said projecting part, a rack-bar pivoted at its lower end to the rear end of said lever and extending upwardly on the inside of said standard, and means, substantially as described, for imparting an endwise movement to said rack-bar for elevating or depressing the platform, substantially as described. 75

4. In a freezing apparatus of the character 80 described, the combination, with the sleeve b^2 , having a bearing-socket in its lower end, the spindle F, loosely inclosed by said sleeve and having a recess in its lower end, and means 85 for imparting rotary motion to said sleeve and spindle in opposite directions, of a vertically-movable platform J and the cream-receptacle G, and agitator H, carried thereby, said receptacle and agitator being adapted to simultaneously engage with the sleeve b^2 and shaft 90 F, respectively, upon the upward movement of the platform J, substantially as described.

WILLIAM H. HOPKINS.
